[57] CLAIM

The ornamental design for a leaf and cuttings gatherer, as shown and described.

DESCRIPTION

FIG. 1 is a top plan view of a leaf and cuttings gatherer showing my new design;

FIG. 2 is an enlarged left side elevation view thereof;

FIG. 3 is an enlarged right elevation view thereof;

FIG. 4 is an enlarged fragmentary plan view of the portion within the circular broken lines shown in FIG. 1;

FIG. 5 is an enlarged fragmentary plan view of a leaf and cuttings gatherer showing a second embodiment of my new design, the sole difference from the first embodiment being in the string hole reinforcement grommets in the periphery thereof.

FIG. 2

FIG. 3

FIG. 5

FIG. 4

FIG. 1
